(57) **CLAIM**

The ornamental design for an article of footwear with integrated sensor, as shown and described.

DESCRIPTION

FIG. 1 is a front, top perspective view of an article of footwear with integrated sensor showing my new design;

FIG. 2 is a rear, bottom perspective view thereof;

FIG. 3 is a top plan view thereof;

FIG. 4 is a bottom plan view thereof;

FIG. 5 is a right side view thereof;

FIG. 6 is a left side view thereof;

FIG. 7 is a front elevation view thereof; and,

FIG. 8 is a rear elevation view thereof.

The broken lines throughout the various figures are included for purposes of illustrating the environment only, forming no part of the claimed design.
